CLAIM

The ornamental design for a tripod head, as shown and described.

DESCRIPTION

FIG. 1 is a front perspective view of a tripod head in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a front perspective view of the tripod head of FIG. 1 showing a ball joint inside the tripod head cavity.

The broken lines shown in the drawings depict portions of the tripod head that form no part of the claimed design.

1 Claim, 7 Drawing Sheets
